UNITED STATES PATENT OFFICE.

JAMES E. ELKINS, OF NEEDLES, CALIFORNIA.

GAME.

1,100,549.

Specification of Letters Patent. Patented June 16, 1914.

Application filed May 18, 1912. Serial No. 698,231.

To all whom it may concern:

Be it known that I, JAMES E. ELKINS, a citizen of the United States, residing at Needles, in the county of San Bernardino 5 and State of California, have invented new and useful Improvements in Games, of which the following is a specification.

The present invention relates to blocks employed in playing various games.

10 The primary object of the invention is the construction of a block having its faces provided with removable characters, each of the series of which being employed in playing a certain game.

15 I also aim to provide a block of this character having suitable pockets for the reception of members bearing certain characters which are required in playing a certain game.

20 With the above recited objects in view and others of a similar nature which will be more apparent as the nature of the invention is more fully disclosed, the improvement resides in the novel construction and 25 arrangement of parts set forth in and falling within the scope of the appended claim.

In the accompanying drawing, Figure 1 is a perspective view of a block constructed in accordance with the present invention;

30 Fig. 2 is a similar view with the plates having the indicating characters removed. Fig. 3 is a top plan view of a plurality of plates having the letters or characters which when attached to the blocks provide for the playing of one game. Fig. 4 shows a reverse view of one of the plates having characters whereby another game may be played.

35 The block 1, which is employed with my improvement is illustrated in the accompanying drawing as rectangular in form, but it is to be understood that the said block may be constructed in various forms and shapes, all of which, however, present any desired number of flattened faces. Furthermore, the blocks may be constructed of any desired or preferred material, and the said block 1 has each of its six faces provided with pockets 2. Each of the said pockets is adapted to receive a plate 3, and the said pockets are preferably of a depth to permit of the face of the said plate lying flush with the face of the block. The plates are removably retained within the pockets in

any desired manner. In the showing of the drawing I have provided the plates with 55 oppositely arranged perforations 4, the same being adapted for the reception of securing elements such as screws 5. By such an arrangement, it will be noted the series of plates bearing different characters may be 60 inserted or removed from the pockets 2, and thus any number of games may be played with the employment of the block. In the present instance the blocks are provided with plates bearing the letters employed in 65 the spelling of the word "travel". When one of the plates is inscribed with a complete word, the remainder of the plates have only portions of the word. In playing this game the blocks employed are six in number, each one of which having a plate bearing the complete word "travel" upon one of its faces, while the remaining faces of each of the blocks are provided with plates showing different parts of the word 70 "travel", and the word parts on each face of the blocks differing from the word parts on any other block, the latter being so arranged that the blocks may be rolled to bring their faces to match or to spell the 75 complete word.

In playing the game the score is determined as follows: For instance, if the word "travel" appears upon the upper face of each of the six blocks the player will of course, score the highest number of points for which the game is played, while the rolling of the blocks bringing to the upper face of the blocks the next highest number of plates bearing the word "travel" or letters 90 making up the highest number of the said word "travel" will entitle the player to the next highest score and so on until the desired number of points played for is totaled by one of the players. 95

Of course a different game may be played by removing the plates to reverse the same and again inserting the said plates within the pockets, and furthermore it is to be fully understood that any number of plates bearing given characters whereby other games may be played may be employed as heretofore stated. 100

The game materially differentiates from the ordinary dice game by reason of the specific arrangement of the letters on the re- 105

spective faces of the blocks, whereby the desired combination can be oftener produced thus adding to the interest of the game.

Having thus described the invention, 5 what I claim is:

A game apparatus including a plurality of cubical blocks, one face of each block having a complete word indicated thereon, the remaining faces of the respective blocks 10 having parts of said word indicated thereon, the word parts differing on each face of a

block and differing from the word parts on any other block, the corresponding faces of all blocks presenting data together completely indicating the word.

In testimony whereof I affix my signature in presence of two witnesses.

JAMES E. ELKINS.
